WALTER ELMENHORST AND FRANZ O. MATTHIESSEN, OF JERSEY CITY,
NEW JERSEY.

Letters Patent No. 77,017, dated April 21, 1868.

IMPROVEMENT IN CENTRIFUGAL MACHINES FOR DRAINING SUGAR.

The Schedule referred to in these Letters Patent and making part of the same.

TO ALL WHOM IT MAY CONCERN:

Be it known that we, WALTER ELMENHORST and FRANZ O. MATTHIESSEN, both of Jersey City, in the county of Hudson, and State of New Jersey, have invented a new and useful Improvement in Centrifugal Sugar-Machines, of which the following is a full, clear, and exact description, reference being had to the accompanying drawing, forming part of this specification, and in which—

Figure 1 represents a sectional elevation of a centrifugal sugar-apparatus having our improvement applied to it;

Figure 2 a plan of the same, and

Figure 3 a horizontal section taken as indicated by the line *z z* in fig. 1.

Similar letters of reference indicate corresponding parts.

This our improvement has reference to that description of centrifugal sugar-machines commonly known as the German machine, and which employ what is termed a rubber-bearing for steadyng and easing the run of the screening or purging-cylinder, and dispense with that costly and solid foundation which is a necessary element or adjunct to other machines of a different character, as regards their support or run, and that employ fixed bearings.

To these lighter and cheaper-hung or supported German machines, however, there has heretofore been a serious objection, due to the wabbings or vacillations of the revolving cylinder, as it approximates a given velocity, and which is apt to scatter the sugar, provided the machine be charged while standing; consequently it is customary not to charge the same till a certain velocity has been acquired by the cylinder; but in purging the lower grades of sugar, that are generally more or less smeary, it makes considerable difference, as regards dry purging, whether the machine is charged while standing, and then set in motion, or filled whilst in rapid rotation. Charging before starting will invariably give a better result, but, as hereinbefore stated, this is not practicable with safety in machines not running in fixed bearings, but supported or steadied by rubber ones, and in the case of thin stuff or lower grades of sugar, is seldom or never practised, but the machine almost invariably first set in motion, and when in full and rapid rotation, feeding in the charge, thereby avoiding those excessive wabbling motions, but producing an inferior or less thoroughly purged sugar.

Our invention has for its object the charging of such machines while standing, without subjecting them to such objectionable and violent wabbling motions that cause the charge to be thrown around, and if not stopped in time, increase so as to become destructive to the machine, and, by scattering the sugar, dangerous to the attendants or bystanders. These violent wabbling movements usually occur when the machine is running at a velocity of from three hundred to five hundred revolutions per minute, but, at a higher speed, cease; that is, when a sleeping or top-spinning velocity has been acquired.

Our invention in this connection, therefore, consists in providing the vertical shaft of the screening or purging-cylinder with a temporarily-acting tie or brace, capable of being shipped or unshipped from its action on the shaft as a bearing or steadyng support while the machine is running, and whereby said cylinder is steadied in its run, till reaching or rather passing the velocity at which the excessive vacillations occur, when, without stopping the machine, said additional support or bearing is thrown off or disconnected from the shaft so as to leave the cylinder with its charge free to spin at the higher velocity acquired without restraining it from those moderate vacillations that are so advantageous in thoroughly purging the sugar, and that take place during the spinning or sleeping run of the cylinder, when not restrained by fixed bearings.

In view of the preceding observations, the following succinct description will suffice to explain how our invention is or may be carried into practice—

A, in the accompanying drawing, representing the screening or purging-cylinder; B, its vertical shaft, and C the outer or surrounding case. D is the step for the lower end of the shaft B to turn in and rest upon, and E the usual steadyng-socket, carried by rubber bands or strips E' E', and, in connection with the socket, form-

ing what is known as a rubber bearing. The requisite rotary motion may be given to the shaft B and purging-cylinder A, by pulleys *b b* and belt or band *c*. To steady the run of the cylinder A till after the velocity at which the excessive wobbling movement occurs has been passed, without restraining subsequent vacillations, and whereby the machine may be charged in advance of starting to run it, and lower grades of sugar be purged in a dry or thorough manner, we, as hereinbefore referred to, apply a temporary brace or tie to the shaft B, in a dry or thorough manner, we, as hereinbefore referred to, apply a temporary brace or tie to the shaft B, until say, for instance, a brace, F, hinged as at *e*, and formed with an eye, *d*, to form a bearing for the shaft B, until a sleeping or spinning velocity has been communicated to the charged cylinder A, or till such time as its violent wobbling movement has been overcome, when said brace may be thrown back or unshipped from the shaft, and the cylinder left free to gently vacillate and aid in the purging of the sugar. Thus, in fig. 1, the brace or bearing F is shown in black lines as down or in gear with the shaft B, and as unshipped or thrown back in red lines.

What is here claimed, and desired to be secured by Letters Patent, is—

In a centrifugal machine of the character described, and having no upper fixed bearing, the combination, with the purging-cylinder A and rubber or elastic bearing to the shaft B, of a removable or adjustable bearing-brace or tie to said shaft, so hung or arranged as that it may readily be thrown in or out of steadyng support to the cylinder while the machine is in motion, essentially as and for the purpose or purposes herein set forth

W. ELMENHORST,
F. O. MATTHIESSEN.
